(57) CLAIM

The ornamental design for a drawer divider, as shown and described.

DESCRIPTION

FIG. 1. is a perspective view of a drawer divider showing the design;

FIG. 2. is a second perspective view thereof;

FIG. 3. is a front elevation view thereof;

FIG. 4. is a rear elevation view thereof;

FIG. 5. is a left side elevation view thereof;

FIG. 6. is a right side elevation view thereof;

FIG. 7. is a top plan view thereof; and,

FIG. 8 is a bottom plan view thereof.

The broken lines illustrate structural features of the drawer divider that form no part of the claimed design.
